HINGE CONSTRUCTION

Joseph George Joachim, Detroit, Mich., assignor
to Ferro Stamping & Manufacturing Company,
Detroit, Mich., a corporation of Michigan

Application May 20, 1940, Serial No. 336,265

2 Claims. (Cl. 16—135)

This invention relates generally to hinge constructions and refers more particularly to improvements in concealed hinges of the type employed for mounting rear deck closures on motor vehicle bodies.

It is one of the principal objects of this invention to provide a relatively simple, compact hinge having means forming an assembly therewith for assisting movement of the closure in one direction and for holding the closure in one extreme position of adjustment.

Another advantageous feature of the present invention resides in the provision of a hinge having a movable part and having spring actuated linkage secured as a unit on the hinge at opposite sides of the path of travel of the movable part in such a manner as to not only counterbalance the weight of the closure to which the movable part of the hinge is connected, but to also effectively hold the closure in its open position.

Still another object of this invention resides in the provision of a hinge assembly of the type previously set forth capable of being inexpensively manufactured, assembled and installed.

The foregoing, as well as other objects, will be made more apparent as this description proceeds, especially when considered in connection with the accompanying drawings, wherein:

Figure 1 is a fragmentary sectional view of a portion of a vehicle body showing my improved hinge assembly in side elevation;

Figure 2 is an end elevational view of the hinge assembly shown in Figure 1;

Figure 3 is a sectional view taken substantially on the plane indicated by the line 3—3 of Figure 1;

Figure 4 is a sectional view taken on the plane indicated by the line 4—4 of Figure 1;

Figure 5 is a cross sectional view taken on the plane indicated by the line 5—5 of Figure 1;

Figure 6 is a cross sectional view taken substantially on the plane indicated by the line 6—6 of Figure 1.

In Figure 1 of the drawings, I have illustrated a portion of a swinging closure 10 hingedly connected to a support 11 by means of a hinge assembly 12 forming the subject matter of this invention. The hinge assembly 12 is particularly applicable to vehicle bodies for pivotally connecting the rear deck closures to the adjacent body structure, although it may be used to advantage in supporting practically any type of swinging closure having sufficient weight to render the use of counterbalancing means practical.

In detail, the hinge assembly is provided with

5 a fixed bracket 13 comprising a pair of laterally spaced plates 14 having transverse flanges 15 at the rear ends thereof attachable to the support 11 and having the opposite ends integrally connected by means of a transverse portion 16. In ordinary installations, the bracket 13 is secured to the support 11 in such a manner that the plates 14 lie in parallel vertical planes and the transverse connecting portion 16 is arranged at 10 the top of the two plates.

Pivotedly supported on the bracket 13 for swinging movement between the plates 14 is a closure supporting arm 17. As shown in Figure 1, the arm 17 is substantially U-shaped in elevation and 15 one end of the arm is pivotally mounted on a pin 18 extending transversely through the plates 14 of the bracket adjacent the rear end of the bracket. One end of the pin 18 is formed with a shoulder engageable with the adjacent plate 14 and the opposite end of the pin is riveted against 20 the other plate 14.

In the present instance, the swinging arm is 25 formed of a pair of sheet metal stampings 20 welded or otherwise suitably secured in juxtaposition to each other and each stamping is reinforced throughout its length by means of a laterally outwardly embossed rib 21. The ends of the stampings 20 opposite the ends engaging the pin 18 are bent laterally outwardly in the manner shown in Figure 5 and secured to the closure 30 10 by the bolts 19.

In view of the fact that the above type of hinge finds particular use in supporting relatively heavy swinging closures, it is advantageous 35 to counterbalance the weight of the closure and to effectively hold the closure in its raised or open position. The means for accomplishing this result in the present instance forms a unitary assembly with the hinge and comprises a 40 pair of spring operated devices 22 supported on opposite sides of the path of swinging movement of the arm 21. In detail, each device 22 comprises a pair of links 23 and 24 having the adjacent ends pivotally connected together by 45 means of a pin 25. The opposite ends of the links 23 and 24 of each device 22 are respectively pivotally connected to the arm 17 and bracket 13. As shown in Figure 1, the free ends of the links 23 are respectively pivotally connected to 50 opposite sides of the arm 17 intermediate the ends of the latter by means of a pin 26 extending transversely through the arm, and the corresponding ends of the links 24 are pivotally connected to the opposite sides of the bracket 13 adjacent the rear end of the latter by means

of a pair of pins 27 which, of course, are installed so as not to interfere with the movement of the arm relative to the bracket.

The above arrangement is such that when the closure 10 is in its closed position, the links 23 assume the relative positions thereof shown by the full lines in Figure 1 and, when the closure is in its open position, the links assume the relative positions shown by the dot-dash lines in Figure 1. In detail, when the closure is in its closed position, the ends of the links 23 connected to the arm 17 by the pivot 26 assume a position adjacent the rear ends of the links 24 and, when the closure is in its raised or open position, the links 23 assume positions approaching alignment with the links 24.

Carried by the adjacent ends of each pair of links is a spiral or clock type spring 28 having the inner end secured in a transverse slot formed in the outer end of each pin 25 and having the opposite end looped around a transverse projection 29 formed on each link 23 by bending the latter at right angles to its normal plane. It may be pointed out at this time that the pins 25 are secured to the links 24 in a manner to prevent rotation of the pins relative to the links. Upon reference to Figure 6, it will be noted that the pins 25 are in the form of rivets having polygonally-shaped portions 30 engageable in correspondingly shaped openings formed in the links 24.

Referring again to Figure 1 of the drawings, it will be noted that when the closure is in its closed position shown in Figure 1, the two springs 28 apply a force on the links 23 in a direction tending to open the closure 10 and these springs are of such strength that they substantially counterbalance the weight of the closure. As a result, the closure may be readily raised to its open position shown by the dot and dash lines in Figure 1. The extent of movement of the closure to its raised position is limited by a pair of stops 31 struck laterally outwardly from the plates 14 on the bracket and engageable with the bottom edges of the links 24 adjacent the swinging ends of the latter. It will also be apparent from Figure 1 that when the closure is in its open position, the springs 28 exert an upward force on the links 23 and thereby hold the closure in its fully open position. Assuming that the closure is now moved toward its closed position, it will be noted that the projections 29 on the links 23 react against the outer ends of the springs 28 and effect a rewinding of the springs.

Thus, from the foregoing, it will be observed that I have provided a relatively simple, compact hinge construction wherein the counterbalancing means forms an assembly with the hinge and is

capable of being installed as a unit with the latter. It will further be observed that the hinge assembly, including the counterbalancing means, is composed of a relatively few simple parts capable of being inexpensively manufactured, assembled and installed.

What I claim as my invention is:

1. A hinge assembly for pivotally mounting a closure on a support, said hinge assembly comprising a fixed hinge part in the form of a bracket attachable to the support and having laterally spaced side walls, a movable hinge part in the form of an arm extending between the side walls of the bracket and pivotally connected to the latter for swinging movement relative to the bracket, a pair of links positioned on each side of the bracket and having the inner ends thereof pivotally connected together, means pivotally connecting the outer ends of the links to the bracket and arm respectively, a pair of spiral counterbalancing springs having the inner ends respectively connected to the pivotally connected inner ends of the links and having the outer ends respectively engaging the links connected to the arm tending to swing the latter in one direction relative to the bracket, and stops on opposite sides of the bracket positioned to respectively engage the links connected to the bracket to limit movement of the latter links by the springs.

2. A hinge assembly for pivotally mounting a closure on a support, said hinge assembly comprising a fixed part in the form of a bracket attachable to the support, a movable part carried by the closure and pivotally connected to the fixed part for swinging movement relative to the latter, a link positioned on each side of the path of swinging movement of the movable part and having the corresponding ends respectively pivotally connected to opposite sides of the movable part, a second link positioned on each side of the path of swinging movement of the movable part and having the opposite ends respectively pivotally connected to the free ends of the first links and to the fixed part, each of the first mentioned links having a portion intermediate the ends thereof extending transversely of the path of swinging movement of the movable part to form transverse shoulders at opposite sides of the movable part, and a pair of spiral counterbalancing springs having the inner ends respectively connected to the pivotally connected ends of the links on each side of the movable part and having the outer ends respectively engaging the transverse shoulders tending to swing the movable part in one direction relative to the fixed part.

JOSEPH GEORGE JOACHIM.
